UNITED STATES PATENT OFFICE

157,688

COMBINATION COOKING TOP, BACKGUARD, AND SHELF FOR A RANGE

Frank W. Krueger, Saratoga, Calif., assignor to James Graham Manufacturing Co., Newark,
Calif., a corporation of California

Application August 6, 1949, Serial No. 4,329

Term of patent 14 years

(Cl. D81—25)

To all whom it may concern:

Be it known that I, Frank W. Krueger, a citizen of the United States of America, residing at Route 1, Box 292, Saratoga, Santa Clara County, California, have invented a certain new, original, and ornamental Design for a Combination Cooking Top, Backguard, and Shelf for a Range, of which the following is a specification, reference being had to the accompanying drawings, forming a part thereof, in which:

Figure 1 is a perspective view of the combination cooking top, backguard, and shelf for a range, showing the backguard mounted shelf in its raised position embodying my new design;

I claim:

The ornamental design for a combination cooking top, backguard, and shelf for a range, substantially as shown.

FRANK W. KRUEGER.
